UNITED STATES PATENT OFFICE.

ELLSWORTH ADAM CRAWFORD, OF THATCHER, ARIZONA.

PUMPING ATTACHMENT FOR WINDMILLS.

1,228,297.

Specification of Letters Patent. Patented May 29, 1917.

Application filed September 9, 1916. Serial No. 119,255.

To all whom it may concern:

Be it known that I, ELLSWORTH A. CRAWFORD, a citizen of the United States of America, residing at Thatcher, in the county of Graham and State of Arizona, have invented certain useful Improvements in Pumping Attachments for Windmills, of which the following is a specification, reference being had therein to the accompanying drawing.

The present invention relates to improvements in pumping attachments for wind mills, one object of the invention being the provision of a device of this character which will increase the efficiency of the wind mill in that the same will operate efficiently under light winds which at the present time are ineffective.

A further object of this invention is the provision of an attachment which is readily connected in place upon any of the constructions of wind mills and pumping mechanisms now employed, and which will increase the efficiency thereof.

25 In the accompanying drawings:—

Figure 1 is a side elevation of the lower portion of a wind mill tower and pump, showing the present invention applied thereto.

30 Fig. 2 is an enlarged detail view of the side elevation of the attachment *per se*.

Fig. 3 is a top plan view thereof.

Figs. 4 and 5 are detail views thereof.

Referring to the drawings, the numeral 5 designates the pump rod, which is adapted to be reciprocated, and 6 the wind mill tower.

The present attachment consists of a substantially U-shaped frame 7 embodying 40 spaced parallel side arms 8 and the intermediate portion 9, the side arms being provided with a plurality of uniformly spaced openings 10 while the bolt 11 engages the neck portion 12 of a weight 13 and any pair 45 of opposed openings so as to adjustably connect the neck portion 12 between the arms 8. An attaching and supporting block 13' has the outer ends of the arms 8 rigidly connected thereto while the clevis 14

is pivoted to the upper part of the block 50 and serves to pivotally connect the chain 15 thereto.

This chain is led over the grooved and curved outer end 16 of the block which is arranged in close relation to the pump rod 55 and is connected by means of the clevis 17 to the pump rod. The shaft 18 is mounted in the block and is journaled in the tower 11 by means of U bolts 19, this arrangement serving to rotatably mount the counterbalancing means for the pump rod.

In operation, the chain carried clevis is first adjusted upon the pump rod so that the pump rod will be given the proper length of stroke. The weight is now adjusted to balance with the lift of the water, thus equalizing the reciprocation or the up and down stroke of the pump piston and thereby being adapted to relieve excessive lift strain from the wind mill (not shown).

From the foregoing description, it is evident with a device of this character attached or interposed between the wind mill gearing and the pump rod, that an exceedingly light wind will operate the pump rod 75 through the wind mill, it having been found that when the mills without this attachment are standing idle, a mill with this attachment will operate efficiently.

What I claim as new is:—

As a means for counter-balancing a vertically reciprocating rod, a pivotally mounted attaching block having one end curved and grooved and positioned adjacent the rod, a flexible element the respective ends 85 of which are pivotally connected to the rod and to the block while the main portion thereof is trained about the curved and grooved end of the block, a substantially U-shaped frame the side arms of which are 90 rigidly connected at their free ends to the block so as to extend the frame from the opposite end of the block, and a weight adjustably mounted between the arms of the frame.

95 In testimony whereof I affix my signature.

ELLSWORTH ADAM CRAWFORD.
